(57) **CLAIM**

The ornamental design for an assay plate with sample landing mark, as shown and described.

DESCRIPTION

FIG. 1 shows a bottom perspective view of an assay plate with sample landing mark according to one embodiment of the present invention.

FIG. 2 shows a top view thereof.

FIG. 3 shows a bottom view thereof.

FIG. 4 shows a front view thereof.

FIG. 5 is a left side view thereof.

FIG. 6 shows a right side view thereof.

FIG. 7 is a rear view thereof.

FIG. 8 shows a bottom perspective view of the assay plate with sample landing mark according to another embodiment of the present invention.

FIG. 9 shows a top view thereof.

FIG. 10 shows a bottom view thereof.

FIG. 11 shows a front view thereof.

FIG. 12 is a left side view thereof.

FIG. 13 shows a right side view thereof; and,

FIG. 14 is a rear view thereof.

The broken lines in the drawings depict portions of the assay plate with sample landing mark that form no part of the claimed design.

1 Claim, 14 Drawing Sheets
